CURTAIN FIXTURE

William S. Hamm and Frank A. Schuetz, Elkhart,
Ind., assignors to The Adlake Company, Chi-
cago, Ill., a corporation of Illinois

Application August 27, 1936; Serial No. 98,110

4 Claims. (Cl. 156—26)

This invention has to do with curtain fixtures of the type in which the gripping members are retracted from the guides by the rotation of a centrally located knob.

5 The object of the invention is to provide an improved curtain fixture of the type described in which a direct spring pull is exerted against both gripping members at the same time, without any lost motion in the knob or other parts, immediately upon the knob being turned, and without regard to the direction in which it is turned.

10 The new fixture—which is a substantial improvement in some respects over the fixture described in the copending application of William S. Hamm, Serial No. 50,067, filed November 16, 1935—is quite inexpensive to manufacture, can be easily taken apart and put together, is light in weight, will not rattle when jarred, releases instantly, and gives a quick smooth and firm gripping action.

15 While the foregoing statements are indicative in a general way of the nature of the invention, other more specific objects and advantages will be apparent to those skilled in the art upon a full 20 understanding of the construction, arrangement and operation of the parts which have been combined to make up the fixture.

25 One form of the invention is presented herein for the purpose of exemplification, but it will 30 of course be appreciated that the invention is susceptible of embodiment in other structurally modified forms coming equally within the scope of the appended claims.

In the accompanying drawing:

35 Fig. 1 is an inside front view of a window curtain assembly equipped with the new fixture;

Fig. 2 is a vertical longitudinal section through one end of the fixture;

Fig. 3 is a horizontal section through the same 40 end of the fixture;

Fig. 4 is a vertical transverse section, taken on the line 4—4 of Fig. 2;

Fig. 5 is a similar section, taken on the line 5—5 of Fig. 2;

45 Fig. 6 is a similar section, taken on the line 6—6 of Fig. 5; and

Fig. 7 is a vertical longitudinal section, taken on the line 7—7 of Fig. 3, with one of the felt centering blocks removed to show the plate 50 against which it is mounted.

As will be observed in the drawing, the fixture is mounted in a metal tube 10 which is attached to the lower edge of a curtain 11. The fixture includes heads 12 at the ends of the tube which 55 carry rubber shoes 13 for frictional coaction with

guides 14 at the sides of the curtain. The heads 12 are provided with stems 15 which are slidably mounted in hollowed out blocks 16 in the ends of the tube. The blocks 16 are frictionally positioned in the ends of the tube, about midway between the upper and lower edges of the latter, in an enlargement 17 of generally rectangular cross section.

The stems 15 of the heads are reduced in diameter at 18, and springs 19 are positioned in the blocks 16 about the reduced portions of the stems between opposed shoulders 20 and 21 on the stems and blocks. These springs act to project the heads 12 at all times toward the guides 14 to effect a firm frictional engagement of the shoes 13 with the guides.

The inner ends of the stems 15 are screwed into short coupling members 22 which are also slidably mounted in the blocks 16, and the coupling members 22 are pivotally connected by means of pins 23 to the adjacent ends of long sheet metal strips 24. The other ends of the strips 24, which are located near the center of the fixture, are supported centrally within the enlarged portion 17 of the tube 10 by means of felt blocks 25, which blocks fit snugly but slidably within the enlarged portion.

The heads 12 with the shoes 13 are retracted against the yielding resistance of the springs 19 by means of an operating knob 26 which is journaled in the tube 10 midway between the ends of the same. The knob is connected by means of a screw 27 to a hub 28 which is located within the tube in coaxial relation to the knob. The knob has a reduced stem portion 29 which is journaled in a bearing aperture 30 in the front face of the tube, and behind the stem portion 29 the knob is provided with a small diametrically arranged rib 31 which fits into a slot 32 in the opposed face of the hub 28. This interlock effects a rigid connection between the knob and hub, causing the hub to turn with the knob, while permitting ready separation of the parts upon removal of the clamping screw 27.

The hub 28 is connected with the strips 24 by means of two oppositely extending pairs of parallel wire links 33 which are pivotally attached to pins 34 located in an annular groove 35 in the hub and project through apertures 36 in small outturned flanges 37 on the adjacent ends of the strip. Beyond the apertures 36 the links are encircled by coil springs 38 which are compressed between the flanges 37 and washers 39 on the ends of the links. The coil springs 38 are encased within small cylindrical housings 40, which

housings are formed from the curled-up edges of plates 41 which are positioned against the strips 24 behind the felt blocks 25. The plates 41 and the felt blocks 25 are both secured to the strips 5 24 by means of screws 42.

With a curtain fixture such as described any turning movement of the knob 26 in either direction will immediately exert a pull on the heads 12 through the medium of the spring-actuated links 10 33, one of the links in each of the pairs always being in a position wherein it will respond to the turning movement of the knob without any lost motion in the device. The springs 38 are sufficiently compressed to prevent any rattling of the 15 parts, and the resistance to further compression offered by the springs is enough to cause the heads to move as soon as the knob is turned.

Initial adjustment of the shoes 13 with reference to the guides 14 may be obtained by screwing the stems 15 of the heads into or out of the coupling members 22. To prevent any unintentional turning movement of the stems in the coupling members when the heads 12 are for any reason out of the guides, the heads may be made 20 rotatable with respect to the stems by being provided with tubular collars 43 which can rotate freely on the ends of the stems while being held against any axial movement thereon. The collars 43 and the ends of the stems can then be provided with registering apertures 44 through which 25 a small nail or other implement may be passed whenever it is desired to screw the stems into or out of the coupling members.

The fixture can be put together or taken apart 30 very easily. The heads 12, coupling members 22, strips 24, links 33, springs 38 and hub 28 can all be secured together before the mechanism is inserted in the tube 10. By merely unscrewing one 35 of the heads the remaining interconnected parts can be threaded through the tube, after which the end blocks 16 can be placed in position, the separated head 12 replaced, the hub 28 brought 40 into register with the aperture 30 in the tube and the knob 26 fastened to the hub. To take the fixture apart this procedure can of course be 45 reversed.

We claim:

1. In a curtain fixture, heads at the ends of the fixture for engagement with guides at the sides of the curtain, springs for pressing the heads out-

wardly, rods connected with the heads, a rotatable operating member, and links connecting each of the rods with the operating member at points above and below the axis of the latter whereby regardless of the direction in which the member is turned one of the links will immediately exert a direct pull on the rod with which it is connected. 5

2. In a curtain fixture, heads at the ends of the fixture for engagement with guides at the sides of the curtain, springs for pressing the heads outwardly, rods connected with the heads, a rotatable operating member, and links connecting each of the rods with the operating member at points above and below the axis of the latter 10 15 whereby regardless of the direction in which the member is turned one of the links will immediately exert a direct pull on the rod with which it is connected, said links having overrunning connections with the rods. 20

3. In a curtain fixture, heads at the ends of the fixture for engagement with guides at the sides of the curtain, springs for pressing the heads outwardly, rods connected with the heads, a rotatable operating member, and links connecting each 25 of the rods with the operating member at points above and below the axis of the latter whereby regardless of the direction in which the member is turned one of the links will immediately exert a direct pull on the rod with which it is connected, 30 said links having overrunning spring-tensioned connections with the rods.

4. In a curtain fixture, a metal tube for attachment to the lower edge of a curtain, heads at the ends of the tube for engagement with guides at 35 the sides of the curtains, springs for pressing the heads outwardly, rods within the tube connected with the heads, a rotatable operating member journaled in the tube at the center of the same adjacent the ends of the rods, links connecting 40 each of the rods with the operating member at points above and below the axis of the latter whereby regardless of the direction in which the member is turned one of the links will immediately exert a direct pull on the rod with which it is connected, and felt blocks carried by the rods 45 adjacent the links for maintaining the rods centered within the tube.

WILLIAM S. HAMM.
